UNITED STATES PATENT OFFICE.

HECTOR LAUZON, OF CINCINNATI, OHIO.

DESIGN FOR A BOTTLE PROTECTING AND CARRYING DEVICE.

59,662.

Specification for Design.

Patented Nov. 15, 1921.

Application filed March 14, 1921. Serial No. 452,314. Term of patent 3½ years.

To all whom it may concern:

Be it known that I, HECTOR LAUZON, a citizen of France, residing at Cincinnati, in the county of Hamilton and State of Ohio, have invented a new, original, and ornamental Design for a Bottle Protecting and Carrying Device, of which the following is a specification, reference being had to the accompanying drawing, forming a part hereof.

The figure of the drawing is a perspective view of a thermos bottle protecting and carrying device, showing my new design, the bottle being indicated by dotted lines.

I claim:

The ornamental design for a bottle protecting and carrying device as shown.

HECTOR LAUZON.
